DESIGN FOR A MIXER

William L. Roy and Guy F. Roy, Stockton, Mo.

Application February 23, 1934, Serial No. 50,834

Term of patent 3½ years

To all whom it may concern:

Be it known that we, WILLIAM L. ROY and GUY F. ROY, citizens of the United States, residing at Stockton, in the county of Cedar, and State of Missouri, have invented a new, original, and ornamental Design for a Mixer, of which the following is a specification, reference being had to the accompanying drawing, forming a part thereof.

Figure 1 is a front elevation of the mixer showing our new design.

Fig. 2 is a side elevation of the same, and, Fig. 3 is a top plan view of the mixer.

We claim:

The ornamental design for a mixer, as shown.

WILLIAM L. ROY.
GUY F. ROY.
